UNITED STATES PATENT OFFICE

2,535,585

ROOF RULER

Kenneth B. Marquiss, Redlands, Calif.

Application November 5, 1948, Serial No. 58,377

3 Claims. (Cl. 33—92)

1

This invention relates to carpenter's tools, and more particularly to a device for use with a carpenter's square for laying out lengths of rafters and other timbers required for roofs and the like.

A main object of the invention is to provide a novel and improved measuring tool for use in conjunction with a carpenter's square, whereby hypotenuse lengths such as lengths of rafters may be readily determined from a knowledge of the "rise" and "run" of a roof, said tool being very simple in construction, easy to manipulate, and providing quick accurate readings.

A further object of the invention is to provide an improved measuring tool using a carpenter's square in conjunction therewith which enables the user to find the length of a rafter or other inclined member of a building frame or roof structure from data providing the pitch angle of the inclined member, said tool requiring only two simple adjustments to operate, involving only a few parts, being inexpensive to manufacture, and being very compact in size so that it may be readily carried in a carpenter's kit.

Further objects and advantages of the invention will become apparent from the following description and claims and from the accompanying drawings, wherein:

Figure 1 is a top plan view of a carpenter's measuring tool constructed in accordance with the present invention.

Figure 2 is an enlarged detail plan view of the adjustable wing member employed to receive the tongue of the carpenter's square, as employed in the measuring tool of Figure 1.

Figure 3 is a cross-sectional view taken on line 3—3 of Figure 2.

Figure 4 is an enlarged cross-sectional detail view taken on line 4—4 of Figure 2.

Figure 5 is an enlarged cross-sectional view taken on line 5—5 of Figure 1.

Referring to the drawings, 11 designates the main body member of the tool, said main body member comprising an elongated straight bar of suitable rigid material having the downwardly and outwardly inclined marginal flanges 12 and 13. The intermediate portion of body member 11 is formed with an elongated longitudinally extending headed rib 14 on which is slidably mounted a block 15 formed with a window overlying flange 12' in which is secured a cylindrical lens 16. Flange 12 is marked off in inches. Stop abutments 17, 17 are provided at the ends of the rib 14 to prevent the block 15 from being removed from the rib.

Designated at 18 is a channel-shaped wing

2

member having a flat top surface 19 terminating in an enlarged portion 20. Projecting upwardly from portion 20 in alignment with the left margin 21 of channel surface 19 as viewed in Figure 2, is a stud 22 extending through a longitudinal slot 23 formed in the zero end portion of body member 11. A washer 22' is provided on stud 22 beneath body member 11. Threaded on stud 22 is a wing nut 24. The channel member 18 is formed with horizontal outwardly projecting base flanges 25 and 26. The tongue 27 of a conventional carpenter's square, shown in dotted view in Figure 1 is snugly receivable in channel member 18.

15 Pivoted to top surface 19 of member 18 at 28 is a flat arm 29 having a lateral extension 30 which terminates in a downwardly bent operating finger 31 extending parallel and adjacent to the left marginal wall of channel member 18, as viewed in Figure 2. Secured to the inside surface of finger 31 is a leaf spring 32 which bears on said left marginal wall and biases arm 29 clockwise, as viewed in Figure 2. Pivots connected to the end portions of arm 29 are respective laterally extending arms 33 and 34 passing through respective guide sleeves 35 and 36 provided on flat surface 19. The arms 33 and 34 have downwardly bent finger portions 37 and 38 received in openings 39 and 40 formed in the sides of channel member 18 and being clampingly engageable with the side edges of the tongue 27 of the square received in the channel member. By pressing the finger 31 inwardly, arm 29 may be rotated counter-clockwise, as viewed in Figure 2, to release the clamping pressure exerted by fingers 37 and 38.

At the right side of the channel member 18 the wall thereof is cut away over a substantial length, as shown at 49, for a purpose presently to be described.

40 In operation, the device is laid over a steel square with the tongue 27 thereof received in the channel member 18, as shown in Figure 1. The body member 11 is then set to the desired pitch angle by referring to the relative scale values on the outer edges of the tongue and blade of the steel square and is then slid longitudinally until the zero point on the flange 12 is at the intersection of the outer edge thereof with the outer edge of the tongue of the square. Wing nut 24 is then tightened. Finger 31 is then pressed inwardly, releasing the clamping fingers 37 and 38, and the device is then moved along the tongue of the square until the length of the run (on a scale of 1 inch=1 foot) appears on the outer edge of the blade 40 of the square at the intersection of the

edge of flange 12 therewith. Finger 31 is then released, whereby the clamping fingers 37 and 38 again clampingly engage the edges of the tongue of the square. The lens 16 is then moved over the intersection of flange 12 with the outer edge of blade 40. Assuming flange 12 to be calibrated in the same manner as the square, or in a manner having integral relationship with the calibrations of the square, the length of the rafter will then be readable direct'y from flange 12.

Under conditions where the "rise" is in excess of the "run" and the length of the tongue 27 is not great enough to accommodate the wing member 18 in the position of Figure 1, the position of said wing member may be reversed by rotating it 180° from the position of Figure 1. Under these conditions the calibrations on the outer edge of tongue 27 may be observed through the elongated opening 39, enabling the device to be used in the same manner as above described.

It will be seen from the above that the tool provides direct accurate readings of desired rafter lengths and other roofing lengths such as hip, valley and jack rafter lengths without confusion, without complicated calculations and without loss of time.

While a specific embodiment of a measuring tool for use in conjunction with a carpenter's steel square has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A carpenter's measuring tool of the character described comprising an elongated body member provided at one edge with a scale of linear units, a lens slidably mounted for longitudinal adjustment on said body member and overlying the calibrated edge thereof, said body member being formed with a longitudinal slot adjacent the zero end of said scale, a downwardly facing channel member having aligned with one side thereof an upwardly projecting stud passing through said slot, a clamping nut on said stud, whereby said channel member may be angularly and longitudinally adjusted with respect to said body member, an arm pivoted to the channel member, a clamping finger connected to said arm and projecting through a side wall of said channel member, and spring means biasing said arm in a direction to urge the clamping finger inwardly in the channel member, said channel member being formed at the marginal portion thereof opposite said stud with an elongated opening extending along said marginal portion.

2. A carpenter's tool of the character described comprising an elongated body member provided at one edge with a scale of linear units, a lens slidably mounted for longitudinal adjustment on said body member and overlying the calibrated edge thereof, a downwardly facing channel member positioned below said body member adjacent the zero end of said scale, an upwardly projecting stud in alignment with one side of and carried by said channel member and extending through the adjacent portion of said body member, a clamping element engageable with the free end of said stud, an operating finger positioned adjacent the side wall of said channel member and mounted on said member for movement toward and away from said side wall, and spring means carried by the inner face of said operating finger and engageable with the side wall of said channel member for urging the finger away from the side wall of said channel member.

3. A carpenter's measuring tool of the character described comprising an elongated body member provided at one edge with a scale of linear units, a lens slidably mounted for longitudinal adjustment on said body member and overlying the calibrated edge thereof, said body member being formed with a longitudinal slot adjacent the zero end of said scale, a downwardly facing channel member having aligned with one side thereof an upwardly projecting stud passing through said slot, a clamping nut on said stud, whereby said channel member may be angularly and longitudinally adjusted with respect to said body member, an arm pivoted to the channel member, a clamping finger connected to said arm and projecting through a side wall of said channel member, and spring means biasing said arm in a direction to urge the clamping finger inwardly in the channel member.
